UNITED STATES PATENT OFFICE.

ERNEST RHODES, OF HERKIMER, NEW YORK, ASSIGNOR TO STANDARD FURNITURE COMPANY, OF HERKIMER, NEW YORK, A CORPORATION OF NEW YORK.

STOP FOR DESK-SLIDES AND THE LIKE.

1,397,782.

Specification of Letters Patent.

Patented Nov. 22, 1921.

Application filed July 7, 1921. Serial No. 482,970.

To all whom it may concern:

Be it known that I, ERNEST RHODES, a citizen of the United States, residing at Herkimer, in the county of Herkimer and State of New York, have invented certain new and useful Improvements in Stops for Desk-Slides and the like, of which the following is a specification.

This invention pertains to stops for desk 10 slides and the like.

Desk slides after being positioned are commonly held against withdrawal beyond their normal extended position by the use of a screw turned into the same from below 15 and adjacent the inner end thereof, such screw taking against the front bar or portion of the desk. Such an arrangement is at once crude and at times, owing to the desk formation, more or less difficult of 20 accomplishment.

The main object of the present invention is to provide a simple and effective stop, one which may be readily positioned and as 25 readily removed, when for any reason it is desired to entirely withdraw the slide.

The invention is illustrated in the annexed drawings, wherein,—

Figure 1 is a vertical sectional view of so much of a desk as is necessary to illustrate 30 the invention, the slide being shown as being placed or positioned within the desk;

Fig. 2 a like view showing the slide in its extended position and the stop in operative position;

Fig. 3 a cross section on an enlarged scale, taken on the line III—III of Fig. 2; and

Fig. 4 a perspective view of the stop and a portion of the slide.

In said drawings, 1 denotes the desk or 40 table top and 2 the front cross bar or frame which overlies the drawer 3. Said cross bar 2 is spaced away from the under face of the top providing a slot or opening at the front of the desk for the reception of the slide 4, 45 the slide being preferably guided at its edges upon ways 5 and 6 built in the desk or table structure. The slide adjacent its inner end is provided with a countersunk opening, or with an opening having two bores, as 7 and 50 8, for the reception of the stop. Said stop takes the form of a headed pin, the stem whereof is denoted by 9 and the head by 10. Bore 7 is slightly larger in diameter than the stem 9 while the countersink or upper 55 bore 8 is slightly larger than the diameter

of the head. The height or length of the stop is equal to or less than the thickness of the slide, so that when the stop is positioned in the slide in the act of placement of the slide, it will not project either above or below the slide (see Fig. 1). I am thus enabled to position the stop in the slide before the same is pushed in beneath the top 1 and by raising the stop so that its lower end is flush with the bottom face of the slide, to 65 push the slide inwardly without difficulty and without any interference between the stop and the cross bar or frame 2. As the slide is pushed inwardly the lower end of the stop rides on the cross bar, and when it 70 reaches the position in Fig. 2, the stop gravitates so that the lower end of stem 9 drops down in rear of bar 2. The slide, of course can not then be withdrawn so long as the stop remains in its lowered position with the 75 head 10 resting upon the bottom face of the countersunk recess or bore 8. Should it be desired to remove the slide it is only necessary for one to remove drawer 3 and lift the stop so that its lower end will, as the slide is 80 drawn outwardly, pass onto the upper face of the bar 2 or into the position shown in Fig. 1.

While it is preferred to make the stop of a length substantially equal to the thickness 85 of the slide, it is evident that it may be made shorter, so long as the parts are so proportioned that the stop will have a bearing of sufficient extent in the slide and against the cross bar 2 when the slide is pulled out to 90 its full extent.

The term desk as employed in the claims is to be understood as embracing any equivalent structure, such as a table, cabinet, or other article of furniture, in conjunction 95 with which a slide may be employed.

What is claimed is,—

1. In combination with a desk having an opening therein for the reception of a slide; a slide mounted in said opening, said slide 100 having a bore formed therein; a gravitating stop loosely mounted in said bore and adapted, when the slide is positioned in the opening, to drop downwardly and prevent withdrawal of the slide; and means carried by 105 the stop for limiting the downward movement of the stop, said stop being free of any mechanical connection with the slide and readily removable therefrom.

2. In combination with a desk having an 110

opening therein for the reception of a slide; a slide mounted therein, said slide having a countersunk bore formed therein; and a headed pin mounted in said bore, the pin being free to gravitate to position within the bore with its lower end projecting below the under face of the slide.

3. In combination with a desk having an opening therein for the reception of a slide; 10 a slide mounted therein, said slide having a bore of two diameters formed in the same

with the larger bore uppermost; and a headed pin mounted in said bore, the pin being of a length not greater than the thickness of the slide and being of such dimensions that the stem thereof will slide freely through the bore of smaller diameter while the head is free to move within the bore of larger diameter.

In testimony whereof I have signed my name to this specification.

ERNEST RHODES.
